(57) **CLAIM**

The ornamental design for a facsimile machine, as shown and described.

DESCRIPTION

FIG. 1 is a front view of a facsimile machine;

FIG. 2 is a top view thereof; and,

FIG. 3 is a perspective view thereof.

The left, right, rear and bottom views contain no ornamentality and are omitted.

The broken line showing is for illustrative purposes only and forms no part of the claimed design.

1 Claim, 2 Drawing Sheets

FIG. 2

FIG. 1

FIG. 3
